UNITED STATES PATENT OFFICE.

AMOS W. STANDING, OF ST. LOUIS, MISSOURI.

DESIGN FOR A GAME DEVICE.

SPECIFICATION forming part of Design No. 29,195, dated August 9, 1898.

Application filed June 18, 1898. Serial No. 683,859. Term of patent 3½ years.

To all whom it may concern:

Be it known that I, AMOS W. STANDING, a citizen of the United States, and a resident of the city of St. Louis, in the State of Missouri, have invented and produced a new and original Design for a Game Device, of which the following is a specification, reference being had to the accompanying drawings, forming a part thereof.

10 Figure 1 is a plan view of a game device, showing my new design. Fig. 2 is a section thereof on the line 2 2, Fig. 1.

15 As shown in the drawings, the leading or material features of my design consist in the representation of a section of country having a mountainous coast, showing part of an ocean, a bay adjacent to the coast, a narrow

channel connecting the bay with the coast, forts contiguous to the channel and coast, a fleet of war vessels concealed at one side of 20 the bay, a sunken vessel lying across the channel, and a fleet of war vessels outside of the channel.

The whole game device is shown arranged in a box.

Having thus described my invention, the following is what I claim as new therein and desire to secure by Letters Patent:

The design for a game device substantially as herein shown and described.

AMOS W. STANDING.

In presence of—

N. V. ALEXANDER,
GEO. H. KNIGHT.
